[57] CLAIM

The ornamental design for a guitar body, as shown and described.

DESCRIPTION

FIG. 1 is a top front perspective view of a guitar body showing my new design;

FIG. 2 is a top plan view of the guitar body of my design;

FIG. 3 is a bottom plan view thereof;

FIG. 4 is a front elevational view of the guitar body of my design;

FIG. 5 is a rear elevational view of the guitar body;

FIG. 6 is a right side elevational view of the guitar body showing my design; and

FIG. 7 is a left side elevational view thereof.
